The ornamental design for pressed cosmetic powder cake, powder cake container and case assembly, as shown and described.

DESCRIPTION

FIG. 1 is an exploded front perspective view of the ornamental design for a pressed cosmetic powder cake, powder cake container, and case assembly;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 8 is a front perspective view of the pressed cosmetic powder cake, powder cake container, and case assembly in a combined configuration.

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan thereof; and

FIG. 14 is a bottom plan view thereof.

FIG. 15 is a front perspective view of an alternate embodiment of the pressed cosmetic powder cake, powder cake container, and case assembly in a combined configuration.

FIG. 16 is a front perspective view of an alternate embodiment of the pressed cosmetic powder cake, powder cake container, and case assembly in a combined configuration.

FIG. 17 is a front perspective view of an alternate embodiment of the pressed cosmetic powder cake, powder cake container, and case assembly in a combined configuration.

FIG. 18 is a front perspective view of an alternate embodiment of the pressed cosmetic powder cake, powder cake container, and case assembly in a combined configuration; and,

FIG. 19 is a front perspective view of an alternate embodiment of the pressed cosmetic powder cake, powder cake container, and case assembly in a combined configuration.

The broken lines illustrate portions of the pressed cosmetic powder cake, powder cake container, and case assembly and form no part of the claimed design.
